UNITED STATES PATENT OFFICE.

LARENCE SPREITZER, OF HAMMOND, INDIANA, ASSIGNOR TO EDWARD VALVE AND MANUFACTURING COMPANY, OF CHICAGO, ILLINOIS, A CORPORATION OF ILLINOIS.

DIE-HEAD.

1,376,047.

Specification of Letters Patent. Patented Apr. 26, 1921.

Application filed July 5, 1919. Serial No. 308,751.

To all whom it may concern:

Be it known that I, LARENCE SPREITZER, a citizen of the United States, residing at Hammond, in the county of Lake and State 5 of Indiana, have invented a certain new and useful Improvement in Die-Heads, of which the following is a full, clear, concise, and exact description, reference being had to the accompanying drawings, forming a part of 10 this specification.

My invention relates to die heads.

In cutting threads with a die, particularly where a short thread is to be cut on stock of a relatively large diameter, it is necessary 15 that the die be stopped accurately and promptly at the end of the thread, particularly before the die strikes a shoulder or projection on the work.

I am aware that prior to my invention it 20 has been proposed to provide an automatically releasable die which will be automatically opened to release the threaded stock by engagement of a tripping member with a stop secured to or on the ways or other stationary member of the lathe. This has not 25 been satisfactory because it is necessary to have the stock extend from the chuck a uniform distance each time. It has also been proposed to place a stop between the jaws of 30 the die, but many of the devices so far offered along these lines have not possessed all the characteristics desirable in such a device.

My invention provides an improved form 35 of automatically releasable die mechanism which opens the dies under the control of a trigger engaged by the outer end of the stock. Thus the opening of the die is directly controlled by the length of the stock 40 which has been threaded.

My invention further provides improved means for closing the dies, for mounting the same, for adjustment of the dies and for controlling the holding and releasing of the 45 dies. Numerous improvements in detail will be apparent from the following detail description and the accompanying drawings which form a part of the same. The invention is not necessarily limited to the cutting 50 of threads, as the invention may be applied to any analogous use. It is also to be understood that while I have illustrated my invention as applied to the usual form of lathe, the device may be applied to a turret 55 lathe and may be automatically operated

both as to opening the jaws of the die and also closing of the same.

Briefly I provide a main body member which bears guides for the jaws, the jaws being movable toward each other by suitable 60 cam means which may be manually or automatically controlled. The frame also bears detent members which engage in notches or shoulders in the jaws or parts connected to the jaws. An axial or central trigger member 65 is connected to the detent so that when the end of the stock in passing through the dies engages the central trigger member it releases the detents from the shoulders permitting springs to move the jaws outwardly. 70

In order to acquaint those skilled in the art with the manner of constructing and practising my invention I shall now describe in connection with the accompanying drawings one embodiment of the invention. 75

Figure 1 is a side elevation of a die head embodying my invention;

Fig. 2 is a longitudinal vertical section of the same;

Fig. 3 is a horizontal longitudinal section; 80

Fig. 4 is a front elevational view;

Fig. 5 is a fragmentary view illustrating the cam or crank mechanism for closing the jaws of the die;

Fig. 6 is a fragmentary general view illustrating the manner of use of the device; and

Fig. 7 is a perspective view of the forward end of the detent member.

The die head which is shown in the drawings consists of a main frame or body member 1, which in this case is formed in the shape of a rather short thick-walled cylinder with a flange or head portion 2 formed integral therewith. A tail piece or stem 4 is loosely mounted in the rear end of the 90 cylinder closing the bore 3. The fit of this tail piece or stem 4 within the bore of the cylinder is made purposely rather loose so that sufficient play will be permitted to admit of the jaws alining themselves with the 95 stock which is to be threaded. Set screws 5 are threaded into the walls of the cylinder 1 and engage in suitable sockets in the enlarged portion 6 of the tail piece or stem 4 to prevent turning of the tail piece with respect to the cylinder or frame 1. The inner ends of the screws 5 are reduced and these reduced ends fit rather loosely in the holes or sockets provided for them so that the play above described may occur. 100 105 110

- The head of flange 2 is machined and formed to provide guiding surfaces or ways for the slide members 7 and 8 which bear the coöperating die members 9 and 10 respectively. Cover plates 12 and 13 are fastened above and below the slide members 7 and 8 to engage the shoulders 14 and 15 which are formed on the slide members 7 and 8. In this manner a suitable guide is formed.
- 10 The jaws 9 and 10 have cutting faces 17 and 18 respectively, in this case adapted to cut screw threads. The jaws 9 and 10 are mounted upon the slides 7 and 8 in any suitable manner, in this case by means of the set 15 screws 19 and 20, which are mounted in brackets 21 and 22 and the clamping screws 23 and 24 which lie in suitable slots in the die members. The set screws 19 and 20 are provided to adjust the die members in and 20 out. These set screws are mounted in the brackets 21 and 22 which are secured upon the ends of the slides 7 and 8. The clamping screws 23 and 24 are threaded into suitable holes in the slide members 7 and 8 and 25 serve to clamp the jaws in adjusted position. In this manner the jaws are securely fastened to the slide members. The slide members, however, are movable in the guides toward and away from the axis of the frame 30 member 1.
- The slide members are cut away to form a passageway or opening 25 of substantially the same size as the bore 3 in the frame or body 1. Compression springs 26 are set in 35 suitable sockets in the slide members 7 and 8 and tend at all times to push the slide members away from each other. The slide members 7 and 8 are provided with recesses 27 and 28 which provide shoulders adapted to 40 be engaged by the ends of the rods 29 and 30. These rods which serve as detents have their inner ends provided with flat faces for engaging the shoulders so that a fairly large area of contact for supporting the outward 45 thrust of the die members is provided. The extent to which the detents 29 and 30 enter the recesses 27 is limited by shoulders 32 which determine the extent of the flat faces 31, as shown in Fig. 7.
- 50 At their rear ends the two rods 29 and 30 are connected together by a cross bar 33, these rods or detents being pinned or otherwise secured to the cross bar. The rear end of the frame or body 1 is recessed to permit 55 the cross bar to slide back and forth as will be described later. The rods 29 and 30 are reduced in diameter at their rear ends where they pass through the cross bar 33 and the extreme rear ends of these rods are guided 60 in suitable collars 35 and 36 which collars are threaded into suitable sockets in the rear end face of the body member 1. Compression springs 37 and 38 lie between the adjacent faces of the cross bar 33 and the collars 65 35 and 36 tending always to thrust the de-

tents 29 and 30 together with the cross bar 33 toward the front of the device so that the ends of the detent may drop into the recesses 27 and 28 in the slide members 7 to 8.

The disengagement of the detent members 29 and 30 from the recesses in the slide members 7 and 8 is controlled by the trigger member 40 which in this case is formed of a thin plate of steel with its front edge presented toward the forward end of the device. 70 The trigger or contact member 40 is of a length just sufficient to clear the internal diameter of the cylinder or frame member 1 with a little clearance. This finger or trigger member 40 is mounted in the end of a rod 41, the end of which is notched to receive the same, and which rod is guided through the hub 42 of the cross arm member 33. The rod 41 is adapted to be clamped to the cross arm member 33 so that engagement of the stock with the finger or contact plate 40 will force the cross arm 33 and the detents 29 and 30 toward the rear to release the slide members 7 and 8 with their coöperating dies to 85 disengage the stock after the same has proceeded the proper distance inwardly. The finger member 40 and rod 41 are preferably mounted so as to prevent the turning of the same and in this case I have cut a groove or key-way 43 in the upper surface of the rod 90 41 and have provided a clamping member 44 which consists of a rod threaded at its lower end into a suitable opening 45 and a suitable handle or wheel 46 at the upper end. The innermost end of the stem 44 is reduced in 100 diameter to correspond to the width of the slot or keyway 43, this reduced extension 47 being adapted to lie at all times in said slot and to prevent turning of the rod 41 and contact member 40. A spring 48 is placed 105 between the hub 42 of the cross arm 33 and the contact member 40, but this normally serves no function. This spring is employed to push the contact finger and the connected rod 41 forward when the clamping member 110 44 is released so that the adjustment of the trigger may be readily made.

The slide members 7 and 8 may be pushed inwardly by hand to engage the detents 29 and 30, but I have shown crank operated 115 means for performing this function. A bracket 50 is mounted on the upper surface of the body or frame member 1 near the front end of the same and a short crank shaft 51 is journaled in the same. The rear end of the shaft 51 is connected to a handle 52 for turning the shaft. At its other end this shaft 51 is provided with a crank disk 53 having a crank pin 54. The crank pin 54 has a link or rod 55 provided with suitable shoulders 56 and 57 at its lower end as shown in Figs. 4 and 5 for engaging the fingers 58 and 59 of the bell crank levers 60 and 61. The bell crank levers 60 and 61 are mounted on pins 62 and 63 which are set 120 65 130

in the upper corners of the flange member 2. The flange member 2 is slotted out to receive the bell crank levers 60 and 61. At their lower ends the bell crank levers 60 and 61 are connected to the slide members 8 and 7 respectively by the pins 66 and 65 which are threaded into the slide members. The levers are suitably slotted to receive the pins 65 and 66 and the flange member 2 is also slotted to permit movement of the pins in their in and out motion. The link 55 is guided by a pin 70 which is formed as the rearward extension of one of the screws 71 which fastens the cover plate 12 in position.

15 This pin 70 passes through a slot 72 formed in the link. It will be noted that the shoulders 56 and 57 on the lower end of the link 55 are of different lengths because of the eccentric position of said link. The handle 20 52 has been shown in the raised position in the drawings but this handle normally lies down against the body 1 by its own weight.

The operation of the device is as follows: The stem 4 is gripped by a suitable socket or 25 chuck which may in turn be mounted on the feed carriage or on the tail stock of a lathe, as shown at 75 in Fig. 6. It is necessary to provide means for forcing the dies to take hold and the dies will then automatically 30 feed forward. To this end provision should be made to let the device feed itself after the threads are started. The body 1 may be supported solely on the stem 4 or it may be mounted on a rest 76 as shown in Fig. 6.

35 The stock or member to be threaded, as shown at 77, is gripped in a suitable chuck 78 so that it may be rotated for forming the threads.

The die jaws are previously set for the 40 proper diameter of stock to be threaded and the trigger member 40 is set to release the detents 29 and 30 when the stock has advanced a suitable distance in the dies.

The setting of this trigger mechanism is 45 accomplished as follows. The detents 29 and 30 are released either by pushing back on the contact finger 40 or on the handle 46 of the clamping screw 44. The slide members 7 and 8 spring outwardly and hold 50 the detent members 29 and 30 in their rear position. The clamping screw 44 is then released by turning the wheel 46 until the reduced stem 47 disengages the bottom of the groove 43. The rod 41 and contact member 40 then move forward under the influence of the spring 48 to the desired position, which may be measured by a scale or ruler inserted between the jaws 9 and 10. If the stock is to be threaded for a half inch, 55 the front face of the contact finger 40 is set a half inch back of the front edge of the jaws 9 and 10. The handle 52 is then raised to bring the slide members 7 and 8 to their inner positions so that the detents 29 and 30 60 drop into the recesses 27 and 28, holding the

die members 9 and 10 in proper position for threading the stock. It will be noted that the trigger or contact member 40 will move forward a slight distance due to the detents 29 and 30 dropping into their sockets. However, the release of the slides 7 and 8 and of the die members 9 and 10 will occur when the end of the stock has pushed the trigger or contact member 40 back the corresponding distance. The degree to which the stock 75 is to be threaded may thus be suitably controlled. When the jaw members 9 and 10 spring outwardly they release the stock and there is no further tendency for them to feed the same.

80 The body or frame member is made relatively long so that a fairly long thread may be cut. As shown in Fig. 2, the contact or trigger member 40 is set for a relatively long thread. The advantages to be gained 85 by this construction are obvious. The jaw members are held rigidly in place and they release instantly, giving a highly satisfactory operation.

85 It will be understood that the device is capable of modification in form, dimensions and proportions and that the device may be used for other purposes. I do not intend to be limited to the precise construction shown and described.

95 I claim:

1. In combination, a body member having an axial bore and having guides arranged transverse to the bore, slide members mounted in said guides, means tending to force 100 said slide members laterally, cutting jaws secured to said slide members, detent members for the slide members, said detent members being suitably guided on said body member, said slides having shoulders adapted to be engaged by said detent members, a contact member forming a trigger, said contact member being mounted substantially axially of said bore, and being connected to 105 said detent members and spring means tending to hold the detent members in engagement with the shoulders of the slide members.

110 2. In combination, a body member having guides, a pair of slides in said guides, spring means tending to force the slides apart, detent means for holding said slides in inward position, said detent means comprising a pair of rods adapted to be moved axially, a cross bar connecting said rods, spring 115 means for holding the rods in engagement with the slides, a trigger member having its forward end adapted to engage the stock entering the cutting jaws and being guided in said cross bar, and means for adjusting 120 the setting of said trigger member in said cross bar.

125 3. In combination, a pair of slides, a pair of detents comprising rods axially movable, a cross bar connecting said rods, said cross 130

bar having a rod passing through the central portion of the same, said rod having at its forward end means for engaging the stock and screw threaded adjusting means 5 for adjusting the setting of said engaging means, and for preventing the rod from turning in the cross bar.

4. In combination, a body member, a pair of slides guided on said body member, said 10 slides having cutting jaws, spring means tending to force said slides apart, detent means for holding said jaws in inward position, trigger means for disengaging the detent means from the slides, said trigger 15 means being adjustable to control the length of stock operated upon, crank means for moving the slides inwardly and a handle for manipulating said crank means.

5. In combination, a slide member bearing 20 a cutting device, a body member in which said slide member is guided, said slide having a recess forming a shoulder, a detent adapted to enter said recess and carrying a bar, a trigger member connected 25 to said detent, said trigger member comprising a plate set edgewise with respect to the stock fed into the cutting member, and a rod adjustably connecting said plate and said bar.

30 6. In combination, a slide member bearing a cutting device, a body member in which said slide member is guided, said slide having a recess forming a shoulder, a detent adapted to enter said recess, an 35 extension on said detent, a trigger member connected to said detent, said trigger member comprising a plate set edgewise with respect to the stock fed into the cutting device, a rod connecting said plate and said 40 detent extension, and screw threaded adjusting means for adjusting the position of said latter rod to said detent member.

7. In combination, a cylindrical body 45 member having an axial bore, said body member having a flanged head at the front end thereof forming guides, said body member having a stem loosely secured in said hollow bore, slides mounted in the guides on said flanged head, cutting jaws mounted on 50 said slides, said slides having recesses forming shoulders, spring means for forcing said slides apart, rods guided in the walls of said body member, said rods being adapted to enter the recesses and to engage said 55 shoulders, said rods forming detent means, a cross bar connected to each of said rods and a trigger member comprising an outer contact member and a connecting rod, said connecting rod extending through said cross 60 bar and being adjustable in said cross bar.

8. In combination, a cylindrical body 65 member having an axial bore, said body member having a flanged head at the front end thereof forming guides, said body member having a stem loosely secured in

said hollow bore, slides mounted in the guides on said flanged head, cutting jaws mounted on said slides, said slides having recesses forming shoulders, spring means for forcing said slides apart, rods guided in the walls of said body member, said rods being adapted to enter the recesses and to engage said shoulders, said rods forming 70 detent means, a cross bar connected to each of said rods, and a trigger member comprising an outer contact member and a connecting rod, said connecting rod extending through said cross bar and being adjustable in said cross bar, a pair of levers connected to said slides and manual means for 75 operating said levers to force the slides inward against said springs.

9. In combination, a body or frame member providing guides, slides mounted in said guides, spring means tending to force said 80 guides apart, detent means for holding the slides in their innermost position, automatic trigger means for releasing said detents, a pair of levers each connected to one of said slides and common cam means for operating 85 both of said levers to move the slides inwardly against said springs.

10. In combination, a pair of slides, means for forcing said slides outwardly, 90 detent means for holding the slides in inward position, a pair of bell crank levers connected to said slides at one end of each of said levers respectively, manually operable crank means and a link connecting said 95 crank means with the opposite ends of said bell crank levers for moving said slides toward each other.

11. In combination, a movable cutting jaw, a spring for moving the jaw away from the stock, a guide for guiding the jaw laterally, a frame or body member supporting the guide, spring pressed detent means mounted on the frame or body member to hold the jaw against the stock, trigger means engageable by the stock for releasing the 105 detent means against spring tension, a lever engaging said jaw, and means for actuating the lever to move the jaw inwardly into an engaging position.

12. In combination, a body or frame member having a pair of slides, said slides being adapted to carry cutting members, said slides having recesses forming shoulders, rods adapted to engage in said recesses against 110 said shoulders, a cross-bar connecting said rods, spring means tending to force said rods into said recesses, and a trigger member comprising a forwardly extending contact member and a connecting rod for connecting said contact member with said cross-bar, and means for adjusting the connection of said contact member and cross-bar.

13. In combination, a body or frame member having a pair of slides, said slides being adapted to carry cutting members, said slides 120

having recesses forming shoulders, rods adapted to engage in said recesses against said shoulders, a cross-bar connecting said rods, spring means tending to force said rods into said recesses, a trigger member comprising a forwardly extending contact member and a connecting rod for connecting said contact member with said cross-bar, a spring for moving said rod in said bar, and means for locking the rod in an adjusted position.

14. In combination, a body member having guides, a pair of slides in said guides, cutting jaws on said slides, spring means

tending to force the slides apart, means comprising a pair of rods adapted to be moved axially, a cross-bar connecting said rods, spring means for holding the rods in engagement with the slides, a trigger member having its forward end adapted to engage the stock entering the cutting jaws and being adjustably fixed in the cross-bar, and means tending to move said trigger member between said jaws.

In witness whereof I hereunto subscribe my name this 25th day of June, 1919.

LARENCE SPREITZER.
